UNITED STATES PATENT OFFICE

KURT RETTICH, OF JACKSON, MICHIGAN, ASSIGNOR TO REYNOLDS SPRING COMPANY, OF JACKSON, MICHIGAN

DESIGN FOR A COMBINATION TUMBLER HOLDER AND BOTTLE OPENER

Application filed August 20, 1932. Serial No. 44,656. Term of patent 7 years.

To all whom it may concern:

Be it known that I, KURT RETTICH, a citizen of the United States, residing at Jackson, in the county of Jackson and State of Michigan, have invented a new, original, and ornamental Design for a Combination Tumbler Holder and Bottle Opener, of which the following is a specification, reference being had to the accompanying drawing, forming part thereof.

Fig. 1 is a front elevation of a combination tumbler holder and bottle opener showing my new design.

Fig. 2 is a side elevation of the combination tumbler holder and bottle opener shown in Fig. 1.

I claim:

The ornamental design for a combination tumbler holder and bottle opener as shown.

KURT RETTICH.
